UNITED STATES PATENT OFFICE.

ORRIE J. EMMONS, OF PHILADELPHIA, PENNSYLVANIA.

CLAMP FOR CONCRETE-FORMS.

1,257,827.

Specification of Letters Patent. Patented Feb. 26, 1918.

Application filed May 25, 1917. Serial No. 170,938.

To all whom it may concern:

Be it known that I, ORRIE J. EMMONS, a citizen of the United States, residing at Philadelphia, in the county of Philadelphia and State of Pennsylvania, have invented certain new and useful Improvements in Clamps for Concrete-Forms, of which the following is a specification.

This invention relates to an improved concrete form clamp and has as its primary object to provide a device of this character which may be used in connection with various different kinds of forms for holding either one or both walls of the form in proper position.

The invention has as a further object to provide a device of this character employing complementary anchoring members joined by a wire cable and wherein the clamp may be adjusted or tightened without likelihood of twisting off the cable or unduly straining the cable.

The invention has as a still further object to provide an arrangement wherein the clamping bolts employed may be easily removed for displacing the walls of the form and wherein, when the said bolts are so removed, there will be no projecting ends or terminals from the clamp extending from the faces of the walls to cause disfiguration or discoloration.

And the invention has as a still further object to provide a device of this character employing an anchoring member of improved type as well as an improved manner of connecting the said members by a length of wire to form a cable therebetween.

Other and incidental objects will appear as the description proceeds and in the drawings wherein I have illustrated the preferred embodiment of the invention and wherein similar reference characters designate corresponding parts throughout the several views:

Figure 1 is a vertical sectional view showing a number of my improved clamps applied to a conventional type of concrete form.

Fig. 2 is a plan view of the form showing the manner in which the clamp is adapted to hold the side walls of the form together.

Fig. 3 is an end elevation illustrating the manner in which the clamp may be used in any instance where the form is provided with one wall only, this view illustrating

different types of anchoring members for the inner terminals of the clamps.

Fig. 4 is an end elevation illustrating the device used in connection with a form of such construction that by displacing the clamp screws from one portion of the form, that portion of the form may be removed for scrubbing or otherwise treating a portion of the finished concrete wall or other structure while the remaining portion of the form is held in position.

Fig. 5 is a detail perspective view showing the complementary anchoring members of the clamp and the manner in which the connecting wire is threaded therebetween preliminary to being twisted to form a cable connecting the said members, and

Fig. 6 is a detail perspective view showing one of the anchoring members detached.

Referring more particularly to the drawings, I have, in Fig. 1, illustrated a conventional type of concrete form having side walls 10, vertical studs 11, and horizontal braces 12. The present invention comprehends a clamp for connecting and holding the walls 10 in proper spaced relation with the clamp adjustable for positioning the walls toward each other so as to compensate for any shrinkage in the concrete after being poured. In carrying out the invention, I employ, as particularly shown in Fig. 5, complementary anchoring members 13 each having a cylindrical body 14 from the inner extremity of which extend oppositely disposed radial lugs or hooks 15. Connecting the anchoring members are wires 16 and 17 respectively. The wire 16 is first passed back and forth between the anchoring members and is looped around the bodies 14 thereof with the strands of the wire between the said members extending over corresponding sides of the hooks 15 thereof. The extremities of the wire are then passed between and bent around the said strands as indicated at 18. The wire 17 is then applied in like manner but it is looped around the bodies 14 of the anchoring members in a direction opposite to the loops of the wire 16 so that the strands of the wire 17 between the said members extend from the loops of the latter wire over corresponding sides of the hooks 15 opposite to the sides thereof engaged by the strands of the wire 16, the strands of the wire 17 crossing over the strands of the wire 16 within the said hooks.

The free ends of the wire 17 are finally passed between and looped around the strands of the said wire as indicated at 19. With the wires 16 and 17 thus initially positioned, the strands thereof between the anchoring members are twisted longitudinally upon each other to form a cable 20, such twisted portion serving to bind the free ends of the wires within the said cable and 10 surely fasten the wires at their ends.

A pair of the anchoring members, upon being connected as just above described, is ready to be positioned between the walls 10 of the form in the manner illustrated in 15 Figs. 1 and 2, and in this connection it is to be observed that the cable 20 is of such length that the said anchoring members are disposed adjacent to the said walls. In Fig. 1, I have illustrated a transverse clamp 20 disposed adjacent the bottom of the form, a second transverse clamp disposed adjacent the top of the form and a pair of diagonally arranged clamps crossing each other. Fig. 2 more particularly shows the spacing of the 25 transverse clamps longitudinally of the form. In connection with each pair of the anchoring members 18, I employ double ended clamping bolts or elements 21. These bolts are passed freely through the braces 12 30 as well as through the walls 10 and are screw threaded at their inner extremities to engage through the bodies 14 of the said anchoring members. The bolts 21 of each clamp are, of course, arranged in alignment 35 and at their outer extremities are equipped with nuts 22. In connection with the bolts of the diagonal clamps, beveled washers 23 are employed to come between the nuts of the said bolts and the braces 12.

40 As will now be readily understood, the bolts 21 may be adjusted within the anchoring members and the nuts 22 also adjusted upon the bolts for clamping the walls 10 of the form together and supporting the said 45 walls in proper spaced relation. Before the concrete is poured in, spreaders 24 are preferably employed between the walls and these spreaders are removed as the concrete reaches the level thereof. Since the bolts 21 may be 50 rotated independently of the anchoring members, turning of these bolts or adjustment of the nuts 22 cannot twist the cables 20. Consequently, adjustment of the clamps will not act to twist off the cables and since 55 the cables are each formed of a plurality of strands wrapped together, the said cables will have sufficient strength to withstand any ordinary tension upon the bolts 21. Also it is particularly noted that the bolts 21 are 60 adjustable clear through the anchoring members so that the said anchoring members may be adjusted the entire length of the inner threaded portions of the bolts without becoming fixed to the bolts to rotate therewith. 65 This arrangement further guards against

the possibility of twisting off the cables 20. Immediately at the inner sides of the anchoring members 13, the strands of the wires 16 and 17 are straight and converge from the hooks of the said anchoring members to the 70 outer terminals of the twisted portions of the cables 20 to, in effect, form cages 25 for the inner terminals of the bolts 21. The inner terminals of the said bolts may be projected into these cages a considerable distance without coming in contact with the wires so that the threads upon the bolts will not, under ordinary circumstances, become mutilated, while, at the same time, the said cages will hold the concrete away from the 80 inner terminals of the bolts.

After the concrete is set within the form, the bolts 21 are removed when the entire form may be displaced. The openings formed in the faces of the concrete by the said bolts 85 may then be sealed when the concrete wall or other structure will be complete. Sealing of these openings may be easily accomplished, and in this connection, it is to be observed that after the bolts 21 are removed, there 90 will be no projecting ends from the clamps extending from the side faces of the concrete structure such as would cause disfigurement or discoloration. Consequently, after the bolt openings have been concealed, 95 the faces of the concrete structure will have a smooth and finished surface.

It will therefore be seen that I provide a particularly efficient construction for the purpose set forth. Any desired number of 100 the clamps may, of course, be used upon one form and these clamps may, as illustrated in Figs. 1 and 2, be arranged to extend between the walls of the form, as preferred, to effect the bracing thereof. However, in Fig. 105 3, I have illustrated the use of the clamp in connection with a form having only one wall. In this figure, the wall of the form is conventionally shown at 26 and supporting the said wall are the vertical studs 27. Extending longitudinally with respect to 110 the studs are the vertically spaced braces 28. Any suitable number of clamps may be employed and in the drawings, I have illustrated the use of three of the clamps. The 115 anchoring members at the inner terminals of the clamps are removed and the inner ends of the cables 20 secured to anchoring members embedded within the concrete. At 29 I have shown the use of an S-shaped 120 anchoring member. At 30 an anchoring member is employed having oppositely directed lugs at the top thereof for engagement with the cable connected to the said anchoring member, while at 31 I have illustrated the use of a bent rod as an anchoring member. Accordingly, it will be seen that the anchoring members at the inner extremities of the cables may, when the clamp is 125 used with a form having but a single wall, 130

be varied in character and may be of any suitable type. The anchoring members at the outer ends of the cables are positioned adjacent the wall 26 and the clamping bolts 21 are projected freely through the said wall as well as through the longitudinal braces 28 for engagement therewith with the nuts 22 of the said bolts engaged with the braces. When the concrete is set, the bolts 10 are displaced when the form may be removed and the holes made in the concrete by the said bolts sealed as previously described.

In Fig. 4 of the drawings, I have illustrated the use of my improved clamp in connection with a conventional type of form having the walls thereof constructed in sections or panels. In this figure, the walls of the form are indicated at 33. Supporting the said walls are vertical studs 34 held by horizontal braces 35. Any suitable number of the clamps may be arranged to extend between the braces 35 in the manner previously described. After the concrete has partly set, one or more panels of either of the walls 33 may be removed, as illustrated at 36, by displacing the bolts 21 engaging through the said panel or panels. The portion of the face of the concrete wall or other structure thus exposed may be scrubbed or otherwise treated while the remaining portion of the wall will be held intact by the form. After being so treated, the panels taken out may be replaced, the bolts 21 removed again fitted in position and other panels of the walls 33 taken out for treating an additional portion of the face of the wall. My improved clamp thus provides a

particularly efficient device for use in connection with paneled forms or in any instance where it is necessary or desirable to strip a form from the bottom upward without disturbing the portion of the form above. Furthermore, as will be seen in view of the preceding description, my improved clamp may also be used wherever it is found practical to employ tie wires, as in granaries, barns and like structures.

Having thus described my invention, what is claimed as new is:

1. A clamp for concrete forms including an anchoring member provided with oppositely directed lugs, a flexible element having overlapping strands thereof looped over the said lugs around the said member, a second flexible element having overlapping strands thereof looped around the said member and over the said lugs in a direction opposite to the strands of said first-mentioned element with the several strands crossing within the said lugs and thence twisted together to form a securing cable, and a clamping element adjustable through the said anchoring member.

2. A clamp for concrete forms including an anchoring member having oppositely directed lugs extending from the inner extremity thereof, flexible elements looped around the body of the said member and extending at opposite sides of said lugs to provide a securing cable, and a clamping element adjustably engaging the anchoring member and detachably connected therewith.

In testimony whereof I affix my signature.

ORRIE J. EMMONS. [L. S.]
